US0D1008090S

(12) **United States Design Patent** (10) **Patent No.:** **US D1,008,090 S**
(45) **Date of Patent:** **** Dec. 19, 2023**

(54) **AUTONOMOUS VEHICLE**

(71) Applicant: **Move-X Autonomous Driving Technology Co., Ltd.**, Lu'an (CN)

(72) Inventors: **Xijiong Ling**, Lu'an (CN); **Hui Zhang**, Lu'an (CN); **Guoliang Zhao**, Lu'an (CN)

(73) Assignee: **Move-X Autonomous Driving Technology Co., Ltd.**, Lu'an (CN)

(**) Term: **15 Years**

(21) Appl. No.: **29/786,667**

(22) Filed: **Jun. 1, 2021**

(51) LOC (14) Cl. **12-02**

(52) U.S. Cl.

USPC **D12/86**

(58) **Field of Classification Search**

USPC D12/86, 90, 91, 92, 99, 164; D21/424, D21/433, 434, 533

CPC B62D 25/00; B62D 25/06; B62D 33/00; B62D 35/00

(57) **CLAIM**

We claim the ornamental design for an autonomous vehicle, as shown and described.

DESCRIPTION

FIG. 1 is a front view of the design;

FIG. 2 is a rear view of the design;

FIG. 3 is a left view of the design;

FIG. 4 is a right view of the design;

FIG. 5 is a top view of the design;

FIG. 6 is a front left side view; and,

FIG. 7 is a front right side view.

Figure(s) that best shows the key point of protection of the design: FIG. 7.
